UNITED STATES PATENT OFFICE.

PAUL E. SCHOEN, OF TROY, NEW YORK, ASSIGNOR OF ONE-HALF TO HALL, HARTWELL & CO., OF TROY, NEW YORK, A FIRM.

BUTTON-SEWING MACHINE.

953,977.

Specification of Letters Patent. Patented Apr. 5, 1910.

Application filed November 17, 1908. Serial No. 343,820.

To all whom it may concern:

Be it known that I, PAUL E. SCHOEN, a citizen of the United States, residing at Troy, county of Rensselaer, and State of New York, have invented certain new and useful Improvements in Button-Sewing Machines, of which the following is a specification.

The invention relates to such improvements and consists of the novel construction and combination of parts hereinafter described and subsequently claimed.

Reference may be had to the accompanying drawings, and the reference characters marked thereon, which form a part of this specification. Similar characters refer to similar parts in the several figures therein.

Figure 1 of the drawings is a view in side elevation of my improved button-sewing machine. Fig. 2 is a central, vertical, longitudinal section of the work-clamp and button-holder of the same, on an enlarged scale. Fig. 3 is a top plan view of the same. Fig. 4 is a view similar to Fig. 2, showing 25 a portion of the bed and work-plate with the garment inserted therebetween, and the buttonhole-stretching pin located in the buttonhole of the garment. Fig. 5 is a similar view with the work-clamp and button-holder lowered, and the work clamped between the work-clamp and work-plate.

My invention relates to improvements in machines for sewing buttons upon button-holed garments, such as shirts and the like, the principal object of the invention being to facilitate the attaching of the button to the button-member of the garment by stitches inserted through the buttonhole in the buttonhole-member of the garment, and 40 through eyes or holes in the button arranged in line with said buttonhole.

In carrying out my invention in its preferred form, I employ in connection with an ordinary button-sewing machine, a buttonhole-stretching pin located at one side of the button-holder in the line of to-and-fro movement, transversely of the axis of the needle, of the needle, or work, as the case may be, which pin is adapted to enter a buttonhole in the buttonhole-member of the garment, and afford a resistance to the pull exerted upon said member by the operator, whereby the button-member and button-hole-member can be stretched flatly, one 55 above the other, and the button clamped

upon the buttonhole-member in position to be secured to the button-member, by stitches inserted by the needle through the holes in the button and the buttonhole into the button-member.

Referring to the drawings wherein the invention is shown in preferred form, 1, represents the head and, 2, the base or bed of an ordinary button-sewing machine, of a type wherein the needle, 3, has a simple, 65 vertical, reciprocatory motion adapting it to coöperate with the other elements of the stitch-forming mechanism, not shown.

Mounted upon the bed, 2, of the machine is a work-plate, 4, whereon the work is 70 adapted to rest, which plate is mounted in slideways, 5, whereby it is guided in its reciprocating movements, transversely of the axis of the needle.

Fixed to the slide plate, 4, to move therewith, is an overhanging arm, 6, in the head, 7, of which is mounted a vertical, reciprocatory post, 8, to the lower end of which is fixed a foot, 9, which serves both as a presser-foot or clamp for the work upon the 80 plate, 4, and as a chuck or button-holder, the foot being recessed at its front end at, 10, to receive an ordinary button, which is held in position in the chuck by means of a spring, 12, as shown in Fig. 2.

The post, 8, is adapted to be raised by means of a lever, 13, to which is connected one end of a link, 14, leading to a treadle, not shown, and is adapted to be forced downwardly when released from the influence of said actuating mechanism, by means of a coil-spring, 15, whereby said foot is 90 yielded against the work resting upon the work-plate 4.

The work-plate, work-clamp, and button-holder are thus adapted to be simultaneously reciprocated, transversely of the axis of the needle, 3, and they may be so reciprocated in any known manner, as by means of a cam-disk, 16, provided with a sinuous cam-groove, 17, adapted to receive a cam-follower, 18, on the end of a rocker-arm, 19, fixed upon the rock-shaft, 20, upon which rock-shaft is also fixed a rocker-arm, 21, engageable with said slideable work-plate 4.

The cam, 16, may be connected with the main drive-shaft of the machine in any known manner.

Mounted upon the foot, 9, just in rear of the button-holder or chuck, is a buttonhole-

engaging pin, 22, fixed upon the vibratory end of a plate-spring, 23, mounted upon said foot, said pin passing downwardly through apertures in the foot and spring, 12, so that 5 when the foot is raised the point of said pin projects below the plane of the foot and the spring, 12. When the foot is lowered, the spring, 23, permits the pin to yield upon engagement with the work-plate, 4, or the 10 bed of the machine.

The pin, 22, is located in line with the eyes or holes in the button when properly located in the chuck or holder, it being understood that the button is arranged with 15 the holes through which the stitches are to be inserted in a line parallel with the direction of movement of the work.

The operation of the apparatus is as follows: The foot, 9, being raised as shown in 20 Fig. 1, and a button, 24, inserted in the chuck or button-holder, the button-member, 25, and buttonhole-member, 26, of the garment are interposed between the foot and the work-plate, 4, with the button-member 25 resting on said work-plate. The buttonhole-member is then raised until the pin, 22, enters the buttonhole, 27, therein, adapted for use in connection with the button to be attached, whereupon both the button-member 30 and buttonhole-member of the garment are stretched longitudinally by the hands of the operator until the pin, 22, is drawn into the extreme rear end of the button hole-slit, after which a further pull toward the front 35 is exerted upon the fabric by the hand of the operator, which pull is resisted by said pin, and tends to cause the walls of the buttonhole to be drawn into straight parallel lines, whereupon the foot, 9, is depressed by 40 releasing the treadle mechanism, and the work is thereby clamped between the foot and work-plate in the position to which it had been stretched, in which position the buttonhole extends in a line parallel with 45 the direction of movement of the work, and directly above the portion of the button-member to which the button is to be attached. While the work is preferably primarily placed in the machine and straightened out by somewhat stretching the same 50 by the hands of the operator, the final stretching which accomplishes the accurate locating and paralleling of the walls of the buttonhole itself, so as to form a well defined straight slit along the line of movement of the needle transversely of its axial line, is due to the resistant coöperation of the stretching pin. The stitch-forming mechanism is then operated, the needle 55 thereof passing downwardly through the two holes in the button, alternately, and through the buttonhole-slit and button-member until the desired number of stitches have been inserted, whereupon the operation 60 of the stitch-forming mechanism is discon-

tinued, the foot, 9, raised and the garment with the button attached is drawn out of the machine, or to a position adapted for the attaching of the next button. The button-hole being stretched longitudinally and in a 70 line parallel with the direction of movement of the work, causes the stitches to be inserted through the slit of the buttonhole between the parallel walls of the buttonhole and not in such walls or in the fabric of the buttonhole-member. 75

This apparatus insures the locating of the button in proper position and dispenses with the buttoning of the garment after the button has been applied, the garments coming from the machine with their parts buttoned together and ready for folding and packing. There is thus no disarrangement or distortion of the buttonhole, due to the buttoning operation or otherwise, so that 80 it is possible to launder the garment before the buttons are attached and subsequently to attach the buttons, thus avoiding the risk of breaking buttons in the laundering operation. 85

I am aware that it has been proposed to employ in connection with a button-sewing machine, a spreading device for the button-hole, comprising fingers adapted to forcibly separate the buttonhole walls to permit the 90 insertion of the necessary stitches, and I make no claim to such a construction, the manner of operation of my apparatus being essentially different in that the buttonhole is maintained stretched longitudinally with 95 its walls substantially parallel instead of pulled apart laterally during the attaching of the button and to this end the buttonhole-stretching pin of my improved apparatus is located in line with the button-chuck or 100 holder in the direction of to-and-fro movement of the goods instead of at one side of, or on opposite sides of such line. 105

In machines of this character, having two sets of elements, one consisting of the 110 stitch-forming mechanism including a reciprocating needle, and the other of a clamp and button-holder, it is customary to move either of said sets of elements relatively to the other, transversely of the needle, as may 115 be desired.

I have shown and described a machine wherein the set of elements comprising the work-support, work-clamp, and button-holder are moved transversely of the needle 120 and relatively thereto, but I do not wish to be limited to such a construction as either set of elements may be moved as desired.

I have shown the pin, 22, slightly curved or hook-shaped but I do not wish to be limited to such shape as any form of pin may be employed, which is adapted to enter the buttonhole, and offer the necessary resistance to the stretching operation to properly locate the buttonhole-slit. 125

What I claim as new and desire to secure by Letters Patent is—

1. In a machine of the class described and in combination two sets of elements, one consisting of the stitch-forming mechanism, including a longitudinally reciprocating needle, and the other of a work-support, work-clamp and button-holder, one of said sets being movable relatively to the other in a plane transverse to the axial line of the needle; and a buttonhole-stretching pin at one side of the button-holder in line therewith in the direction of movement of said relatively movable set of elements adapted to engage the extremity of the buttonhole.

2. In a machine of the class described and in combination two sets of elements, one consisting of the stitch-forming mechanism, including a longitudinally reciprocating needle, and the other of a work-support, work-clamp and button-holder, one of said sets being movable relatively to the other in a plane transverse to the axial line of the needle; a spring mounted upon said work-clamp and a buttonhole-stretching pin mounted upon said spring and adapted, when the clamp is raised, to project below the plane thereof.

3. In a machine of the class described and in combination two sets of elements, one consisting of the stitch-forming mechanism, including a longitudinally reciprocating needle, and the other of a work-support, work-clamp and button-holder, one of said sets being movable relatively to the other in a plane transverse to the axial line of the needle; a spring mounted upon said work-clamp and a buttonhole-stretching pin mounted upon said spring and adapted, when the clamp is raised, to project below the plane thereof, said pin being located at one side of the button-holder in line therewith in the direction of movement of said relatively movable set of elements.

4. In a machine of the class described, and

in combination, two sets of elements, one consisting of the stitch-forming mechanism, including a longitudinally reciprocating needle, and the other of a work-support, work-clamp and button-holder, one of said sets being movable to and fro relatively to the other in a plane transverse to the axial line of the needle; and a hook-shaped buttonhole-stretching pin at one side of the button-holder in line therewith in the direction of movement of said relatively movable set of elements adapted to engage the extremity of the buttonhole.

5. In a machine of the class described, and in combination, stitch-forming mechanism, including a longitudinally reciprocating needle; a work-support, work-clamp and button-holder together movable to and fro in a plane transverse to the axial line of the needle; and a buttonhole-stretching pin at one side of the button-holder in line therewith in the direction of movement of said to-and-fro movement adapted to engage the extremity of the buttonhole.

6. In a machine of the class described having two sets of elements, one consisting of the stitch-forming mechanism, including a longitudinally reciprocating needle, and the other of a work-support, work-clamp and button-holder, one of said sets being movable to and fro relatively to the other, in a plane transverse to the axial line of the needle, a pin mounted at one side of the button-holder, in line therewith, in the direction of movement of said relatively movable set of elements, said pin being adapted to enter and engage the extremity of a buttonhole in the work beneath the buttonholder.

In testimony whereof, I have hereunto set my hand this 15th day of November, 1906.

PAUL E. SCHOEN.
